UNITED STATES PATENT OFFICE

135,852

DESIGN FOR A BOMBARDMENT AIRPLANE

Paul H. Kemmer, Patterson Field, and Charles S. Butt, Jr., and Carl E. Reichert, Dayton, Ohio

Application October 23, 1942, Serial No. 108,598

Term of patent 7 years

To all whom it may concern:

Be it known that we, Paul H. Kemmer, Charles S. Butt, Jr., and Carl E. Reichert, citizens of the United States, residing at Patterson Field, in the county of Greene and State of Ohio; Dayton, in the county of Montgomery and State of Ohio; and Dayton, in the county of Montgomery and State of Ohio, respectively, have invented a new, original, and ornamental Design for a Bombardment Airplane, of which the following is a specification, reference being had to the accompanying drawings forming a part thereof, wherein:

Figure 1 is a top plan view of a bombardment airplane illustrating our new design;

Figure 2 is a front elevational view of the airplane illustrated in Figure 1;

Figure 3 is a side elevational view of the said airplane design illustrated in Figure 1;

Figure 4 is a perspective view of the novel airplane design.

We claim:

The ornamental design for a bombardment airplane, as shown.

PAUL H. KEMMER.
